UNITED STATES PATENT OFFICE.

JOHAN R. BAKSTAD, OF CHICAGO, ILLINOIS, ASSIGNOR TO HOLDEN & WHITE, INC.,
OF CHICAGO, ILLINOIS, A CORPORATION OF ILLINOIS.

ELECTRIC HEATER.

1,396,241.

Specification of Letters Patent.

Patented Nov. 8, 1921.

Application filed October 7, 1920. Serial No. 415,291.

To all whom it may concern:

Be it known that I, JOHAN R. BAKSTAD, a citizen of the United States, and a resident of Chicago, in the county of Cook and State of Illinois, have invented certain new and useful Improvements in Electric Heaters, of which the following is a specification.

The invention relates to electric heaters of a character adapted to the heating of passenger cars and pertains more particularly to a novel heater which may be applied under the seats of the car. My invention is well adapted for street cars and the like and particularly to cars having cross seats.

The heater of my invention comprises a novel casing of sheet metal having a top plate, an inclosed Cutler-Hammer heating element and outwardly projecting end hanger-flanges adapted to be secured on bars supported on the angle iron rails usually found at the front and rear edges of the car seat frames. The heater extends longitudinally of the car seat, and is suspended suitably below the seat-cushion by novel hanger members forming a part of the heater and positioned on cross-bars whose ends are secured to the usual front and rear rails of the seat framing.

The body casing of the heater of my invention is of elongated trough-shape generally speaking and has a bottom and downwardly converging sides, at whose upper edges are flanges to receive the covering or top plate, which is removable to expose the heating element within the casing. The sides and bottom of the casing may be formed of one integral piece of sheet metal and are perforated to permit of the exit of the heated air; and the ends of said casing may each be formed of an integral piece of sheet metal and secured by electric welding or otherwise to the body of the casing, the upper edges of said ends, above said body casing, being formed integrally with outwardly projecting flanges which are to be secured upon cross-bars applied to the seat-frame. The cross-bars may be applied in any desired location below the cushion of the car seat, and the heater of my invention may be supported from said bars and hence be positioned in a manner which may be found most convenient and effective.

The heater of my invention is compara-

tively light in weight, compact, efficient and capable of being easily installed.

The invention will be fully understood from the detailed description hereinafter presented, reference being had to the accompanying drawings, in which:

Fig. 1 is an end elevation, partly in section and partly broken away, of a well known type of car seat equipped with an electric heater embodying my invention;

Fig. 2 is a vertical longitudinal section through a portion of the same, taken on the dotted line 2-2 of Fig. 1;

Fig. 3 is a top view of the heater shown as suspended by cross-bars from the angle iron rails of the seat frame, said rails being shown as partly broken away;

Fig. 4 is a longitudinal section, partly broken way, through the same, taken on the dotted line 4-4 of Fig. 3, and

Fig. 5 is a transverse section through the same, taken on the dotted line 5-5 of Fig. 4, and showing the body-casing, cover-plate and fastening screws as juxtaposed for assembling.

In the drawings, I illustrate, in Fig. 1, a car seat of known type, 10 designating the cushion and 11 the general frame thereof. The frame 11 usually embodies front and rear angle bars or rails 12.

The heater of my invention is designed to be suspended below the cushion 10 and supported from the angle bars or rails 12 by means of cross-bars 13 whose ends rest upon and may be bolted to the horizontal flanges of said bars 12.

The heater comprises a main or body-casing 14 of sheet metal and of general trough outline and a cover plate 15 for the upper end of said casing. The casing 14 comprises a bottom 16, downwardly converging sides 17 and ends 18, said bottom and sides preferably being in one integral piece of sheet metal bent to form and perforated for the escape of heated air from within the casing. The upper edges of the sides 17 have formed therewith laterally extending horizontal flanges 19 and return inwardly bent flanges 20, the flanges 20 preferably in their normal condition inclining downwardly and inwardly to a slight extent from the flanges 19, as shown in Fig. 5. The flanges 19, 20 are perforated, as at 21, and the perforations in the flange 20 are threaded, and said flanges at said perforations receive screws 22 by 110

means of which the cover-plate 15 may be fastened against the flanges 19 and directly over the casing 14. The cover-plate 15 is plain and flat throughout its middle portions and its front and rear parts incline upwardly and outwardly so as to serve as deflectors 9 for the heated air leaving the casing 14. The cover plate 15 contains holes to receive the screws 22, and, as shown in Fig. 3, three screws at each side of the plate 15 are sufficient for securing said cover plate in position. It is desirable that there be no rattling between the cover-plate 15 and the casing 14, and hence the flanges 20 are normally deflected downwardly and inwardly from the flanges 19 so that when the screws 22 are applied for securing the cover plate in position, said flanges 20 may be drawn upwardly to a slight extent toward the flanges 19 by said screws and exert a spring action tending to lock the screws 22 in position and bind the cover-plate 15 so firmly upon the flanges 19 that no rattling of the parts may take place during the travel of the car. The flanges 19, 20 serve to properly support the cover 15 and also add material strength to the upper edges of the casing 14, and the folding over of the metal at the upper edges of the sides 17 to form the flanges 19, 20 affords such strength to the upper edges of the casing that the latter may be made from sheet metal of reasonable thinness, thereby decreasing the weight and expense of the heater as well as increasing the efficiency thereof.

The ends 18 of the heater are preferably each in one integral piece of sheet metal and at their sides and lower ends conform generally to the outline of the casing 14 in cross-section, and said ends 18 are formed at their side and lower edges with right angle flanges 23, 24, respectively, which closely receive and are secured by welding or otherwise to the ends of the casing 14, which is seated upon the flanges 24 and held at the ends of its sides 17 between the flanges 23, the latter terminating suitably below the flanges 20 so as not to interfere therewith. The ends 18 extend upwardly above the body of the casing 14 to create vertical hanger-members 25 and at their upper edges said members 25 are formed with laterally extending flanges 26 which are horizontally disposed and project outwardly in opposite directions from the heater and are adapted to rest upon and be secured by bolts 27, or other suitable means, to the cross bars 13, as I illustrate in Figs. 3 and 4. The ends 18 are preferably permanently secured upon the ends of the body casing 14. The cover-plate 15 sets downwardly between the vertical members 25 of the ends 18 and said members 25 create adequate air spaces above the plate 15 and between said plate and the adjacent portions of the car seat above the same. The

members 25 having the flanges 26 form hangers by which the heater may be readily applied to the cross-bars 13. The car seat frame usually has the rails 12 and the additional equipment required for securing my heater in position simply comprises the bars 13. The bars 13 will be located along the angle bars or rails 12 in such position as may render the use of the heater most efficient, and the provision of said cross-bars 13 adapts the heater to be properly secured in any desired position with relation to the parts of the car seat and adapts the heater to car seats varying materially in details of construction. The bars 13 may be secured along the rails 12 in any position desired, and the heater may be secured in any position desired along the bars 13, thus permitting the heater to be located centrally below the car seat or toward the front or back thereof and to such position lengthwise of the car seat as the occasion may render more desirable. The holes for the screws or bolts 27 by which the heater is secured to the cross-bars 13 may be formed at any suitable points along said bars, as may be determined during the installation of the heaters, and the holes for the bolts 28 by which the bars 13 are secured to the angle rails 12 may be formed at any suitable points along said rails that may seem to be most desirable during the installation of the heaters.

The heater comprises, aside from the heating element, two main units, to-wit: the trough like casing 14 having the ends 18 secured thereto and the cover-plate 15 which may be applied to and removed from the casing 14 whenever desired. The entire heater may be readily removed from the car seat, and should the car seat be equipped with a metal plate below the cushion 10, as is sometimes the case, the cover plate 15 may be omitted. I prefer to employ the cover plate 15, however, because said plate closes the upper end of the casing 14 and protects the heating element located within the casing and also serves to prevent the heat from acting against the cushion 10. I may add that the doubled-over flanges 19, 20 which receive the cover-plate 15 are important, since they not only strengthen the casing 14, but properly receive and prevent rattling of the said cover-plate 15. I have mentioned that the openings 21 in the flanges 20 are threaded, but I find that the threading is not important, since when the flanges 20 are inclined, as shown, the thread on the screws 22 will engage the lowermost edge of said openings in said flanges 20 and operate to draw the flanges 20 toward the flanges 19, thereby creating the spring action hereinbefore referred to.

I have hereinbefore described all of the features of the heater with the exception of the heating element, which I number as a

whole 29. The heating or resistance element 29, except in respect to its end features and means for mounting the same within the casing 14, is of known commercial type and

5 commonly designated as the Cutler-Hammer unit. This unit, as is well-known, comprises a ribbon of flat nichrome wire which is wound around a flat mica core and firmly inclosed in a flat steel casing which, in the drawing, 10 I number 30. A strip of mica is located between the ribbon and the casing 30 and provides the necessary electrical insulation, as usual.

The Cutler-Hammer unit is more particularly described in Letters Patent No. 795,747, dated July 25, 1905, and No. 811,859, dated February 6, 1906. The heating unit comprises a bar 31 extending lengthwise thereof and projecting beyond the same, as shown

20 in Fig. 3, and held by the sheet metal folded-over casing 30, and I utilize the ends of this bar as means for mounting the resistance element within the casing 14. Within the

25 casing 14 at each end thereof, I secure upon the bottom of the casing an insulating block 32, whose construction is more particularly illustrated in Fig. 5, and upon the blocks 32 I mount angle iron supports 33 which are formed of sheet metal and have their horizontal flanges bolted to the blocks 32 and

30 their vertical members 34 extended upwardly at one side of the bar 31, and I secure the ends of the bar 31 to said vertical members 34 by means of screw bolts 35, as shown in

35 Figs. 4 and 5, said screw bolts extending through the vertical members 34 and through suitable openings in the bar 31, and said bolts being insulated from said bar by mica disks 36. It is to be noticed that the resisting

40 element may be handled as an entirety and applied to and removed from the casing 14 at will. 37, 38, respectively, indicate the conductors for the element 29, and they extend through one end of the casing 14, as

45 shown in Fig. 4, and are secured at their terminal ends to the element 29 by means of screw-bolts 39 which permit of the ready application of said conductors to and their removal from the heating element 29. It is

50 of considerable advantage that I am enabled to mount the element 29 within the body casing 14 by means of the simple angle irons 33, since in this manner no complication is caused in the method of mounting the ele-

55 ment 29 and said element may be conveniently located centrally of the casing 14 and also be conveniently removed from said casing whenever occasion may so require.

What I claim as my invention and desire

60 to secure by Letters-Patent, is:

1. In combination, a car seat frame, cross bars extending between the front and back rails thereof and an electric heater for suspension from said cross-bars, said heater

comprising a horizontally elongated perforated body casing having sides and ends which extend upwardly beyond said sides and are flanged to seat upon said cross bars, whereby the heater becomes suspended suitably below the car seat.

2. In combination, a car seat frame, cross-bars extending between the front and rear portions thereof, an electric heater for suspension from said cross bars comprising a body casing of general trough outline in cross-section having perforated sides, a bottom, ends and end members which extend upwardly beyond said sides and carry flanges to seat upon said cross bars, whereby the heater becomes suspended suitably below the car seat, and a cover-plate secured upon said sides and extending beyond the same.

3. In combination, a car seat frame, an electric heater, and means suspending said heater from said frame below the car seat, said heater comprising a body portion of general trough outline in cross-section having perforated sides, a bottom, ends and a cover-plate, said sides having at their upper edges outwardly extending and return flanges to receive said cover plate, said return flanges being slightly inclined downwardly and inwardly, and both said flanges and said cover plate being perforated to receive securing screws, the inclination of said return flanges affording a spring action for binding said cover-plate noiselessly upon said casing.

4. In combination, a car seat frame and an electric heater for suspension from said frame below the car seat comprising a body casing of general trough shape in cross-section having perforated sides, a bottom, ends and a cover plate secured upon the said sides, said ends conforming to the outline in cross-section of said casing and having bottom and side edge flanges receiving and welded to the end portions of said body casing.

5. In combination, a car seat frame, an electric heater and means suspending said heater from said frame below the car seat, said heater comprising a body portion of general trough outline in cross-section having perforated sides, a bottom and ends, a cover plate applied over said casing, a heating element within said casing comprising a longitudinal bar set on edge, angle iron supports connected with the bottom of the casing and having upright members alongside of the ends of said bar and means detachably connecting said ends to said upright members.

Signed at Chicago, in the county of Cook, and State of Illinois, this 27th day of September, A. D. 1920.

JOHAN R. BAKSTAD.
